UNITED STATES PATENT OFFICE.

IRA G. NICKS, OF DENVER, COLORADO, ASSIGNOR TO THE JOY TOY MANUFACTURING COMPANY, OF DENVER, COLORADO, A CORPORATION OF COLORADO.

TOY AEROPLANE VEHICLE

Application filed March 20, 1926. Serial No. 96,269.

This invention relates to improvements in toy vehicles for children and has special reference to improvements in that type of toy vehicles that resemble an aeroplane and which are therefore sometimes referred to as toy aeroplanes.

It is the object of this invention to produce a toy of this kind that shall be suitable for young children that are learning to walk and which will amuse them and assist them in their efforts to learn to walk properly.

The invention can be best understood and most clearly described when reference is had to the accompanying drawing in which it has been illustrated and in which:

Fig. 1 is a top plan view of the invention;

Fig. 2 is a side elevation with parts broken away to better disclose the construction;

Fig. 3 is a section taken on line 3-3, Fig. 1;

Fig. 4 is a front elevation looking in the direction of the arrows 4 in Fig. 1, parts being broken away to better disclose the construction;

Fig. 5 is a section taken on line 5-5; Fig. 2 and shows the manner in which the rear wheel is secured in place; and

Fig. 6 is a section taken on line 6-6, Fig. 1.

This device, instead of having a chassis frame formed from a plurality of bars has a base that is made from a piece of board 1 whose outline is somewhat cigar shaped and which has two openings 2 and 3 separated by a narrow connecting portion 4. The openings 2 and 3 are for the purpose of accommodating the legs of the child who sits on the top of the board 1 or the part 4. Secured to the underside of the board 1 near the rear pointed end is a U-shaped bracket having sides 5 and a base portion 6. This bracket is held in place by means of bolts 7 that pass through the board 1 and the base 6 in the manner shown in Fig. 5. Secured to the lower ends of the arms 5 so as to be rotatable in a plane that lies intermediate the arms 5 is a wheel 8 that is preferably provided with a rubber tire. Secured to the underside of member 1 by means of bolts 10 is a bracket 11 whose length exceeds the width of the member 1 and whose outer ends have a downwardly inclined portion 12 and terminate in a horizontal portion 13.

Secured to the horizontal ends 13 by means of a connector 14 and bolts 15 are tubular members 16 to which the caster wheels 17 are rotatably connected by means of inclined brackets 18.

Secured to the edges of the base or board 1 is a sheet metal housing 19 whose upper surface is cut away in the manner indicated by numeral 20 so as to provide an opening for the child's body. That portion of the housing that lies to the front of the opening 20 represents the engine hood or cover and secured to this is a plane 21 that lies parallel to the surface on which the vehicle is supported and which extends outwardly to each side like the wing of a monoplane. This plane is secured to the casing by means of bolts 22 that extend through it and through the inturned edges 23 of the casing 19 in the manner shown in Fig. 4. Braces 24 have their lower ends secured to the underside of the board 1 by means of bolts 25 and have their upper ends secured to the underside of the plane 21 by means of bolts 26.

The front end of the housing is closed by a plate 27 to the front side of which a piece of expanded metal 28 is secured. The expanded metal is held in place by a frame 29 that is fastened to the plate 27 by means of bolts or rivets 30. The parts 28 and 29 produce an appearance like that of an ordinary radiator such as is now used in connection with automobiles and aeroplanes. In order to more closely simulate the appearance of an aeroplane a propeller 31 is pivoted at 32 to the center of the area of exposed expanded metal. Secured to the rear end of the vehicle are two vanes 33 and 34 which resemble the horizontal and vertical rudders of an aeroplane. A metal bar 35 is secured at its ends to the underside of the plane 21 and has a portion that extends parallel with the rear edge of the plane in the manner indicated in Fig. 1. This bar forms a hand grip that can be engaged by the child in operating the vehicle. The upper surface of the plane 21 forms a table upon which the child may keep its playthings.

From the above it will be seen that I have produced a toy vehicle that is so constructed that it can be used by very young children while learning to walk and which has the appearance of a monoplane. I desire to call

particular attention to the construction employed in attaching the front or caster wheels as well as the manner in which the plane is secured in place so as to form a table on which the child may keep its play things.

Having now described the invention what is claimed as new is:

A toy vehicle, wheeled supports, a seat secured to the supports, the seat having its

sides cut out to receive the legs of the occupant, forward extending side walls on the seat, a table member secured on the side walls in advance of said cut outs and a transverse handle bar secured at the rear edge of and lying in approximately the plane of said table.

In testimony whereof I affix my signature.

IR A. G. NICKS.
